METHOD AND APPARATUS FOR PRODUCING
FIBERSGeorge S. McElroy, Granville, Ohio, assignor to
Owens-Corning Fiberglas Corporation, a cor-
poration of Delaware

Application January 11, 1949, Serial No. 70,561

11 Claims. (CL 49—17)

1

This invention relates to an improved method and apparatus for manufacturing fibers from glass or materials having characteristics similar to glass.

One of the objects of this invention is to provide an efficient process and a simple and inexpensive apparatus for making fine fibers. A body of heat softened material is subjected to the combined action of centrifugal force and the force produced by an extremely hot high velocity blast of gas. In accordance with this invention the body of heat softened material is deposited upon a rotor adjacent the peripheral edge of the latter and is drawn out by the action of centrifugal force into the path of a blast of gas moving at a velocity sufficient to attenuate the heat softened material into fine fibers.

Another object of this invention is to direct the blast of gas in the general direction of flow of heat softened material leaving the peripheral edge of the rotor and at a sufficient angle to the plane of rotation of the rotor to cause the blast of gas to engage the heat softened glass just as it is released from the peripheral edge of the rotor. The arrangement is such that the blast of gas applies a radial force component on the glass of sufficient magnitude to continue attenuation of the glass in a generally radially outward direction and prevent the glass from flowing or falling back as it moves beyond the influence of the centrifugal force. Thus the heat softened glass discharged from the periphery of the rotor is maintained within the attenuating zone of the blast, and is effectively drawn out from the rotor into fibers.

Still another object of this invention is to provide apparatus wherein the attenuating blast of gas is supplied by a plurality of high velocity burners of the internal combustion type arranged in two annular groups respectively located above and below the rotor. The burners of the top group are supported to direct blasts of gas toward the peripheral edge of the rotor in a generally radially outward direction from the axis of the rotor and the burners forming the bottom group are supported to direct their respective blasts of gas toward the peripheral edge of the rotor also in a generally radially outward direction. As a result the blasts of gas from the bottom group of burners act to prevent the heat softened glass or material leaving the rotor from dropping under the influence of gravity and in addition cooperate with the blasts of gas issuing from the burners in the top group to attenuate the heat softened material or glass into fibers. It is also important to note that the

2

blasts apply the attenuating force to the glass at about the same time the glass moves beyond the influence of the centrifugal force so that the glass continues to travel outwardly from the rotor periphery.

A further object of this invention is to provide an arrangement of the above general type wherein the burners in the top group are staggered with respect to the burners in the bottom group in a manner to provide a substantially ring-shaped blast of gas moving generally radially outwardly from the peripheral edge of the rotor. Also, with the above arrangement, an undulating motion is applied to the glass leaving the periphery of the rotor and this action tends to increase the attenuating force, because greater lengths of the glass are presented to the force of the blasts.

A still further object of this invention is to provide a construction wherein the material deposited on the peripheral portion of the rotor is heated or maintained at the desired attenuating temperature by radiant-type combustion burners supported at opposite sides of the rotor and alternating with the high velocity burners.

The foregoing as well as other objects will be made more apparent as this description proceeds, especially when considered in connection with the accompanying drawings, wherein:

Figure 1 is a semi-diagrammatic vertical sectional view through the apparatus embodying the features of this invention;

Figure 2 is a plan view of the construction shown in Figure 1;

Figure 3 is a bottom elevational view of the construction shown in Figure 1;

Figure 4 is a fragmentary elevational view of a part of the apparatus;

Figure 5 is a longitudinal sectional view through one of the high velocity burners;

Figures 6 to 8 inclusive are respectively fragmentary sectional views showing different types of rotors; and

Figure 9 is a fragmentary plan view showing another modified form of the invention.

It will be apparent as this description proceeds that the present invention may be successfully employed in the manufacture of fibers from various types of inorganic or synthetic materials which may be drawn out into fine fibers when in a softened condition. However, the invention has been developed for the particular purpose of manufacturing glass fibers, and accordingly, the apparatus is described below in connection with the use of glass as the fiber forming material.

Referring now more in detail to the structure

shown in the drawings, it will be noted that the reference numeral 10 designates a rotor supported for rotation about a vertical axis and having a centrally disposed hub 11 secured to the bottom of a tubular vertical shaft 12. The shaft 12 is journaled in bearings 13 spaced from each other and secured in a fixed port 14. The shaft 12 is rotated by a prime mover such for example as an electric motor 15 having a drive shaft 16 operatively connected to the upper end of the shaft 12 through the medium of a belt 17.

Supported at each side of the plane of rotation of the rotor 10 is a group of high velocity burners of the internal combustion type and these burners are arranged in concentric relation to the axis of rotation of the rotor. The group of high velocity burners at the top of the rotor is designated generally by the numeral 18 and the group of high velocity burners at the bottom of the rotor is indicated generally by the numeral 19. The burners in both groups are identical in construction and a description of one will suffice for all. As shown in Figure 5 of the drawings, each burner comprises a combustion chamber 20 having high temperature resistant refractory walls 21 and having a metal casing 22 surrounding the walls 21. The metal casing 22 has a part 23 at the inner end of the combustion chamber which is fashioned to provide a gas inlet chamber 24. The gas inlet chamber is separated from the combustion chamber by a wall 25 having a multiplicity of passages 26 through which fuel gas mixture flows into the combustion chamber from the inlet chamber 24. The outer end of the combustion chamber in each burner is formed with a restricted outlet opening 27 through which the products of combustion taking place within the chamber 20 escape into the atmosphere in the form of an intensely hot high velocity blast B to be more fully hereinafter described.

A combustible mixture of gases is simultaneously supplied to each of the inlet chambers 24 of the top group of burners 18 by an annular manifold 28 supported in concentric relation to the rotor shaft 12 above the rotor and respectively connected to the inlet chambers 24 through conduits 29. The desired combustible mixture of gases is supplied to the manifold 28 through the medium of a conduit 30 which extends from a source of supply to the manifold 28.

A second manifold 31 is located directly below the rotor and is connected to the inlet chambers 24 of each of the burners in the group 19 through conduits 32. The desired combustible mixture of gases is supplied to the manifold 31 by a conduit 33 which extends coaxially through the tubular rotor shaft 12 and is connected at the upper end to the source of supply.

It will also be noted from Figure 1 of the drawings that a feeder or tank 34 is suitably supported directly above the rotor 10 and is adapted to contain a supply of molten or heat softened glass. The feeder 34 has an outlet opening 35 in the bottom wall through which molten glass flows in a downward direction in the form of a stream 36 and the feeder is so positioned with respect to the rotor that the stream of glass 36 is deposited on the rotor adjacent the periphery of the latter. The peripheral edge portion of the rotor is heated by two groups of radiant-type burners respectively indicated by the reference characters 37 and 38. The burners 37 are respectively arranged between the adjacent high velocity burners in the group 18 and the burners 38 are respectively positioned between the high velocity burners in the

group 19. The burners 37 are connected to the manifold 28 by conduits 39 and the burners 38 are connected to the manifold 31 by conduits 40. As a result, a combustible mixture of gases from the same source supplying the high velocity burners in the groups 18 and 19 is supplied to the two groups of radiant burners 37 and 38. The burners 37 are positioned to direct their respective flames downwardly against the top surface of the peripheral edge of the rotor 10 and the burners 38 are located to direct their respective flames against the bottom surface of the peripheral edge of the rotor. The purpose of these burners is to maintain the glass deposited on the top surface of the rotor in a molten or heat softened condition, or in other words to maintain the glass at such a viscosity that it will flow in a radially outward direction along the rotor under the influence of centrifugal force obtained by rotating the rotor. The speed of rotation of the rotor 10 about the axis of the shaft 12 depends to a great extent on the viscosity of the glass deposited on the peripheral edge portion of the rotor and is sufficient to provide the centrifugal force required to flow the glass radially outwardly from the periphery of the rotor.

Referring again to Figure 1 of the drawings, it will be noted that the burners in the two groups 18 and 19 are so positioned with respect to the plane of rotation of the rotor 10 that the blasts B issuing from the outlet openings 27 in the burners intersect the plane of rotation of the rotor immediately beyond the peripheral edge of the rotor and also travel in a generally radially outward direction with respect to the axis of rotation of the rotor. The arrangement is such that the blasts apply a resultant radially outwardly extending force on the glass as it leaves the periphery of the rotor and this force maintains the general radial orientation of the glass after the glass travels beyond the influence of the centrifugal force. Thus the blasts B cooperate to continue the drawing out process of the glass and reduce the glass to fine fibers. It is also important to note that the blasts B issuing from the burners in the group 19 serve to support the glass as it leaves the peripheral edge of the rotor and prevents the glass from dropping under the action of gravity.

The high velocity burners in the group 18 are shown herein as staggered with respect to the corresponding burners in the group 19 so that the blasts B issuing from the respective burners cooperate to form a substantially continuous annular blast around the periphery of the rotor. However, it will be understood that the burners in the two groups may be positioned in direct vertical alignment so that the blasts from the burners in the top group impinge against the blasts from the burners in the bottom group. In the event such a construction is provided the burners in the two groups are arranged so that the blasts impinge directly beyond the peripheral edge of the rotor and coact to attenuate the glass leaving the rotor into fine fibers. In cases where the burners in the two groups are staggered with respect to one another an undulating motion is applied to the glass leaving the periphery of the rotor. This whipping action presents greater lengths of the glass to the force of the blasts and aids materially in drawing out the glass to form very fine fibers.

It follows from the above that regardless of the particular arrangement of the burners in the two groups 18 and 19 the blasts B issuing from the

outlet openings 27 of the burners cooperate to apply generally radially outward force components on the glass as it leaves the periphery of the rotor and before the glass has an opportunity to cool to any appreciable extent. The velocity of the blasts B or the radial force component of these blasts is sufficiently high to attenuate the heat softened glass into fine fibers.

In order to obtain blasts B having the required characteristics, the size of the outlet opening 27 is so proportioned with respect to the quantity of gas burned within the combustion chambers 20 that the products of combustion are forced through the outlet openings 27 in the form of blasts having a temperature which exceeds the softening temperature of glass and having a velocity sufficient to draw out the softened glass into fibers. In practice it is possible to so proportion the size of the burner outlet openings with respect to the combustion chambers that the blasts of gases issuing from the outlet openings have a temperature as high or higher than 3000° F. and a velocity as high or higher than 1,200 feet per second. It will, of course, be understood that the temperature and velocity of the burned gases issuing from the burners may be proportionately varied by changing the size of the outlet openings 27 with respect to the volume of the combustion chambers 20.

Also in practice various different types of combustible gas may be used to obtain the blasts B but for reasons of economy it is preferred to use an ordinary fuel gas, such as natural or manufactured fuel gas. The fuel gas employed is mixed with the proper amount of air by means of orthodox air and gas mixers not shown herein. The gas and air mixture is taken from the mixer at moderate pressures of approximately one to five pounds per square inch but may be considerably higher if desired. This mixture is supplied to the manifolds 28 and 31 in the manner previously described and is burned substantially entirely within the combustion chambers 20. As a result, a very high rate of expansion takes place within the chambers 20 and the walls of the chambers become extremely hot, so that the rate of combustion actually exceeds the rate of flame propagation of the combustible mixture of gases in the atmosphere.

Although the burners 37 and 38 are supplied with the same combustible gas, nevertheless the outlet openings in these burners are relatively large in comparison to the volume of the burner chambers so that the velocity of the burning gases directed toward the rotor is relatively low. In other words, the purpose of the burners 37 and 38 is merely to maintain the glass in such a fluid state that it will flow radially outward under the influence of the centrifugal force. In this connection, attention is called to the fact that the stream 36 of glass is deposited on the rotor 10 at one or more points adjacent the peripheral edge portion of the latter which is directly heated by the radiant burners. As a result, any tendency for the glass to cool as it flows along the rotor is avoided and the glass is maintained at a more uniform viscosity.

Inasmuch as the stream 36 of molten glass is deposited on the rotor adjacent the periphery of the latter there is a tendency for the lower portion of the stream to move in the direction of the rotor. This may be counteracted by directing a blast of gas against the lower portion of the stream 36 as it contacts the rotor. In Figure 4 of the drawings a burner 45 similar to the burners

18 or 19 is supported in a position to direct the blast of gas issuing therefrom in a direction opposite the direction of rotation of the rotor and against the lower end of the stream of glass 36.

In some instances it may be advantageous to separate the heat softened glass into a multiplicity of streams as the glass leaves the peripheral edge of the rotor. This is accomplished in Figure 6 of the drawings by forming an up-standing flange 46 at the periphery of the rotor and by serrating the top edge of the flange to form a plurality of circumferentially spaced grooves 47. Thus as the heat softened glass flows radially outwardly over the serrated edge of the flange 46 under the influence of centrifugal force it is divided into a multiplicity of streams 48. These streams are immediately subjected to the action of the high velocity blasts B and are attenuated into fine fibers.

Figures 6 to 8 inclusive show different types of rotor constructions designed to separate the heat softened glass into individual streams. In Figure 7 the periphery of the rotor is formed with a series of generally radially outwardly extending teeth 49. In Figure 8 the peripheral edge of the rotor is flared upwardly slightly and is serrated to form points 50. This arrangement also serves to divide the glass into individual streams.

If desired, the burners in one or both groups may be oriented to discharge their respective blasts of gas at a slight angle to the periphery of the rotor, as shown diagrammatically in Figure 9 of the drawings. The angle is determined to direct the blasts issuing from the burners in the direction of rotation of the rotor so the force of the blasts counteract any tendency for the glass leaving the peripheral edge of the rotor to fall back and wrap around the rotor. Otherwise the construction shown in Figure 9 is the same as the first described form of the invention, and the same reference numerals are used to designate corresponding parts.

Although particular stress has been placed above on the use of a blast of gas composed substantially entirely of products of combustion for attenuating the glass leaving the periphery of the rotor, it should be understood that blasts of practically any gas having the required heat and velocity characteristics may be used. For example, blasts of steam or superheated air may also serve the purpose required.

I claim:

1. Apparatus for producing glass fibers comprising a rotor supported for rotation about a substantially vertical axis, a series of burners supported at opposite sides of the plane of rotation of the rotor for directing hot high velocity blasts of gases toward the peripheral edge of the rotor and in a direction extending substantially radially outwardly from the peripheral edge of the rotor, means for depositing heat softened glass on the top surface of the rotor, a series of burners for heating the peripheral edge of said rotor, means for rotating the rotor at a speed determined to provide the centrifugal force required to flow the heat softened glass in a generally radially outward direction over the top surface of the rotor and into the blast of gas, and means at the peripheral edge of said rotor for separating the heat softened glass into a multiplicity of individual streams.
2. Apparatus for producing glass fibers comprising a rotor supported for rotation about a substantially vertical axis, a plurality of burners

75

supported at one side of the plane of rotation of the rotor in positions to heat the peripheral edge portion of the rotor, additional burners at opposite sides of the plane of rotation of the rotor for burning a combustible mixture of gases and positioned to discharge the burned gases in the form of hot high velocity blasts in a generally radially outward direction from the peripheral outer edge of the rotor, means for depositing heat softened glass on the heated peripheral edge portion of the rotor, and means for rotating the rotor at a speed determined to provide the centrifugal force required to flow the heat softened glass in a generally radially outward direction over the heated top surface of the rotor and into the high velocity blast of gas.

3. Apparatus for producing glass fibers comprising a rotor supported for rotation about a substantially vertical axis, an annular series of individual burners having combustion chambers within which a combustible mixture of gases is burned and having outlet openings so proportioned with respect to the quantity of gases burned in the chambers that the burned gases are forced from the chambers in the form of blasts having a velocity sufficient to attenuate heat softened glass into fibers, means supporting the burners at one side of the rotor in positions to direct the blasts in a generally radially outward direction from the peripheral edge of the rotor, a complementary series of burners disposed on the opposite side of said rotor for directing a corresponding attenuating blast in the direction of said first named blast, means for depositing heat softened glass on the top surface of the rotor, and means for rotating the rotor at a speed determined to provide the centrifugal force required to flow the heat softened glass in a generally radially outward direction over the top surface of the rotor and into the combined blasts of gas.

4. Apparatus for producing glass fibers comprising a rotor supported for rotation about a substantially vertical axis, means for depositing heat softened glass on the top surface of the rotor, means for rotating the rotor at a speed determined to provide the centrifugal force required to flow the heat softened glass in a generally radially outward direction over the top surface of the rotor, an annular series of burners supported at one side of the plane of rotation of the rotor in positions to heat the glass as it flows radially outwardly along the top surface of the rotor, and an annular series of burners supported at the opposite side of the plane of rotation of the rotor in positions to direct blasts of extremely hot gas toward the peripheral edge of the rotor and in a generally radially outward direction to attenuate the heat softened glass leaving the peripheral edge of the rotor to form fibers.

5. Apparatus for producing glass fibers comprising a rotor supported for rotation about a substantially vertical axis, means for depositing a heat softened glass on the top surface of the rotor, means for rotating the rotor at a speed determined to provide the centrifugal force required to flow the heat softened glass in a generally radially outward direction over the top surface of the rotor, two series of burners supported at opposite sides of the plane of rotation of the rotor in positions to direct blasts of gas toward the peripheral edge of the rotor and in directions extending generally radially outwardly from the rotor, and burners interposed between adjacent burners in both the above mentioned

series and positioned to heat the peripheral edge portion of the rotor.

6. Apparatus for producing fibers comprising a rotor supported for rotation about a substantially vertical axis, means for continuously depositing a heat softened glass on the top surface of the rotor, means for heating the glass at the edge portion of the rotor, means for rotating the rotor at a speed determined to provide the centrifugal force required to flow the heat softened glass in a generally radially outward direction over the top surface of the rotor, and two annular series of burners supported at opposite sides of the plane of rotation of the rotor with the burners in one series staggered with respect to the burners in the other series, said burners being positioned to direct intensely hot high velocity blasts toward the peripheral edge of the rotor and in directions extending generally radially outwardly from the rotor.

7. Apparatus for producing fibers comprising a rotor supported for rotation about a substantially vertical axis, means for depositing a heat softened glass on the top surface of the rotor, means for rotating the rotor at a speed determined to provide the centrifugal force required to flow the heat softened glass in a generally radially outward direction over the top surface of the rotor, two annular series of burners supported at opposite sides of the plane of rotation of the rotor with the burners in one series staggered with respect to the burners in the other series, said burners being positioned to direct intensely hot high velocity blasts toward the peripheral edge of the rotor and in directions extending generally radially outwardly from the rotor, and additional burners supported between adjacent burners in each of the above series and positioned to heat the peripheral edge portion of the rotor.

8. Apparatus for producing glass fibers comprising a rotor supported for rotation about a substantially vertical axis, means for continuously depositing a stream of glass on the top surface of the rotor, means for heating the peripheral portion of said rotor, means for rotating the rotor at a speed determined to provide the centrifugal force required to flow the glass in a general radially outward direction along the top surface of the rotor, and means for directing a high velocity blast of gas against the stream in the region of contact of the stream with the rotor and in a direction opposite the direction of rotation of the rotor.

9. Apparatus for producing glass fibers comprising a rotor supported for rotation about a substantially vertical axis, means for depositing a stream of glass on the top surface of the rotor, means for rotating the rotor at a speed determined to provide the centrifugal force required to flow the glass in a generally radially outward direction along the top surface of the rotor, means for directing a high velocity blast of gas against the stream in the region of contact of the stream with the rotor and in a direction opposite the direction of rotation of the rotor, and means for directing an additional blast of high velocity gas in a direction extending substantially radially outwardly from the periphery of the rotor to attenuate the heat softened glass leaving the peripheral edge of the rotor.

10. The process of producing glass fibers which comprises continuously depositing a body of heat softened glass on the periphery of a rotating member, heating the glass on said member and drawing out the glass in a generally radially out-

ward direction by centrifugal force, and continuing the drawing out process in a radially outward direction as the glass travels beyond the influence of the centrifugal force by introducing the glass between blasts of gas having the temperature exceeding the softening point of glass and having a velocity high enough to attenuate the glass to form fibers.

11. The process of producing glass fibers which comprises continuously depositing a body of heat softened glass on the periphery of a rotating member, heating the glass on said member and flowing the softened glass in a generally radially outward direction to draw out the glass by the action of centrifugal force, and continuing the drawing out process as the glass travels beyond the influence of centrifugal force by progressively introducing the glass leaving the periphery of the rotor into alternate blasts of gas moving up-

wardly and downwardly with respect to the plane of rotation of the rotor in a generally radially outward direction from the periphery of the rotor.
